BURNER

Joseph P. Ring, Wilmington, Mass.

Application February 27, 1934, Serial No. 713,203

3 Claims. (Cl. 126—92)

This invention relates to a burner construction, the general object of the invention being to provide means for supporting a radiant on a burner head in such a manner that there is no danger of the radiant falling from or being knocked from the burner head, while permitting the parts to be separated for cleaning or repair purposes.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Fig. 1 is an elevation showing the radiant supported from the burner head in accordance with this invention.

Fig. 2 is a fragmentary vertical sectional view taken longitudinally of the device.

Fig. 3 is a vertical transverse sectional view through the supporting member, the section being taken substantially on the line 3—3 of Fig. 1.

Fig. 4 is a horizontal sectional view through one end of the radiant, the section being taken on the line 4—4 of Fig. 1.

Fig. 5 is a top plan view of one of the burner nozzles.

Fig. 6 is a section on line 6—6 of Fig. 5.

In these drawings, the burner head is shown at 19 and it is provided with the vertically arranged passages 21, the upper portions of said passages flaring outwardly, as shown in Fig. 2 for the reception of the nozzles 22. Each nozzle is preferably of the construction shown in Figs. 5 and 6, the body of the nozzle being pressed into the flaring end of a passage and the upper end of the body is of substantially rectangular shape in cross section and has a cap 23 fitting thereon, the cap being provided with longitudinally extending slots 23'. Gas and air are supplied to the passages 21 in any suitable manner. Of course, this mixture is ignited as it escapes through the slots 23' in the cap 23 of the nozzles 22.

A radiant support 26 is mounted on the burner head and said support is composed of side and end members, each of substantially angle-shape in cross section with one limb extending upwardly and the other inwardly, the inwardly extending part forming a horizontal shoulder 26' and the inwardly extending parts of the end members each having an opening 28 therein, as shown in Fig. 2. The support 26 is also formed with the

legs 27 which slope downwardly and outwardly, as shown more particularly in Fig. 3 and the lower ends of these legs are notched as shown at 27' to receive portions of the upper edge of the head. A radiant shown generally at 29 has its lower end fitting in the support 26 and resting on the shoulder 26'. This radiant is of any suitable construction though its vertical end members 30 are formed with the exterior channels 31 which are located in vertical alinement with the openings 28 of the support. Loop-shaped members 24 are formed at the ends of the burner head and located beneath said members 24 are the socketed members 25 also formed on the ends of the burner head.

Retaining bars 38, bent as shown in Fig. 2, pass through the openings 28 in the support 26 and have their inwardly offset lower portions engaged in the loops 24 and the lower ends in the sockets 25 while their upper ends are located in the channels 31 so that these bars firmly hold the support 26 on the burner head and the radiant on the support. The radiant is provided with a head 35 having passages 36 therein which communicate with the spaces in the radiant.

Thus it will be seen that the support holds the radiant in spaced relation to the burner head and the parts are firmly held together by the notched legs 27 and the bars 38, it of course being understood that the radiant is heated by the flame of the burner head.

What is claimed is:—

1. In a burner, a burner head having a flat top and vertically arranged sides and ends, a radiant extending over the entire length and width of the head, a supporting member on which the radiant is seated and legs depending from the supporting member and having notches in the inner faces of their lower ends, the walls of which engage portions of the upper face and side and end walls of the burner head.

2. In a burner, a burner head, a radiant, a supporting member on which the radiant is mounted and legs depending from the supporting member and having notches in the inner faces of their lower ends, the walls of which engage portions of the upper face and side walls of the burner head, the ends of the supporting member having openings therein and the ends of the radiant having vertical grooves therein, loop-forming members extending from the ends of the burner head and socket-forming members extending from the ends of said burner head and rods passing through the openings in the ends of the supporting member and through the loop 55

members with their lower ends resting in the sockets of the socket members and their upper portions seated in the grooves of the radiant.

3. In a burner, a burner head, a supporting member, legs depending from the member and engaging portions of the top part of the burner head for holding the supporting member in spaced relation from the burner head, a radiant mounted on the supporting member, socket-form-

ing members extending from the ends of the burner head, the end members of the radiant having grooves therein and rods passing through the ends of the supporting member with their lower ends resting in sockets of the socket members and their upper portions extending into the grooves of the radiant.
